UNITED STATES PATENT OFFICE.

ALLISON A. KOHR, OF MAPLEWOOD, NEW JERSEY, ASSIGNEE TO THE KOPPERS COMPANY, OF PITTSBURGH, PENNSYLVANIA, A CORPORATION OF PENNSYLVANIA.

COKE TREATMENT AND PRODUCT.

No Drawing.

Application filed September 25, 1925. Serial No. 58,493.

This invention relates in general to treatment of cellular carbonaceous residues, such as coke, and is of especial utility in designating the origin of such material so that the 5 domestic purchasers, even though not able to determine the difference in quality of the coke from the cellular formation and arrangement, may quickly and readily determine whether or not other kinds of coke are 10 mixed therewith. More particularly this invention relates to the treatment of coke to improve its flame value from an aesthetic point of view by the admixture of certain substances which will, upon combustion of the 15 coke so treated, produce a colored and easily recognizable flame. The advantages of such coloration of the flame consist in rendering coke from a particular source or sources easily distinguishable, when burned, from all other 20 cokes not so treated, and also in rendering the flames produced in the combustion of the said coke more agreeable from an aesthetic standpoint, when such burning is carried out in the open, as for instance in the open basket type 25 of house heating grade. This type of fixture is often installed for heating rooms in dwelling houses and the like and while coke is recognized as the cleanest and best fuel, an objection which is frequently raised to the use 30 of coke as a fuel in such domestic open grates. is that it produces a less pleasant flame from an aesthetic point of view than wood. The present invention provides means whereby such objections may be overcome.

35 The invention further consists in such other new and useful improvements, and has for further objects such other operative advantages or results, as may be found to obtain in the processes and articles hereinafter described or claimed.

The substances that may be used to produce flame coloration may be those commonly used in the pyrotechnic industry, and well known in that art. In pyrotechnic practice, such 45 substances are generally mixed with potassium chlorate or perchlorate before being added to the combustible material but this has been found not to be absolutely necessary in applying such substances to coke. A summary of the more common chemicals in the 50 follows, but it is understood that the invention is not limited or confined in scope to the employment of any of these substances or any combination or combinations thereof. The 55 invention may be practiced successfully with

the use of any other substances which are found to give the color or combination of colors desired upon combustion of coke that has been suitably treated.

Red colors are commonly obtained by the use of the salts, such as the carbonate, nitrate and sulphate, of strontium and lithium. Blue flames result from the use of the carbonate, sulphide, and arsenite of copper ($CuCO_3$, CuS , and $CuHAsO_3$, respectively), and also 60 calomel ($HgCl$). The nitrate, chlorate and carbonate of barium are used to effect a green coloration, and the oxalate and carbonate of sodium are used when a yellow flame is desired. Such salts are commonly used with potassium chlorate ($KClO_3$) or perchlorate ($KClO_4$), and finely divided magnesium is sometimes added to produce a more brilliant effect. Various colors may also be obtained, 65 without the use of potassium chlorate, by the use of the following materials, or combinations thereof: black oxide of antimony, sulphate of copper, and borax, and numerous other substances some of which are not 70 deemed suitable for use for the purpose described, by reason of the offensive or poisonous character of the products of volatilization.

Preferably, the substances to be used are 75 dissolved or suspended in water, and sprayed upon the coke to be marked, the latter being 80 preferably somewhat above ordinary temperatures. For instance, the substances may be introduced into the quenching water at the place of manufacture of the coke. As an 85 alternate method, the coke may be dipped into 90 solutions or suspensions of the chemical or chemicals used. The preferred manner is to add the material at the final sorting at the coke-screening station of the coke plant.

The term coke, as hereinabove used is 95 meant to designate the cellular carbonaceous residue that is obtained from the distillation in the absence of air of bituminous materials such as coal, coal tar, pitch, shale oil, petroleum, and the like, and is independent of the 100 source or method of carbonization employed, such as ovens of the beehive or by-product type, retorts, and so on.

The broad idea of rendering coke distinctive is described and claimed in the copending application of F. W. Sperr, Jr., Serial No. 58,492 filed of even date herewith for coke treatment and product.

The invention as hereinabove set forth is

embodied in particular forms but may be variously embodied within the scope of the claim hereinafter made.

I claim:

- 5 A method of imparting to coke a distinctive flame coloration characteristic to distinguish it from coke of other origin, which comprises: quenching the freshly made hot coke

with quenching water containing and depositing upon the coke a flame-coloring substance or substances that will impart a characteristic color to the flame of combustion of the coke so quenched. ¹⁰

In testimony whereof I have hereunto set my hand.

ALLISON A. KOHR.
